UNITED STATES PATENT OFFICE

100,129

DESIGN FOR A RADIO CABINET

Robert Z. Snyder, Philadelphia, Pa.

Application February 13, 1936, Serial No. 61,128

Term of patent 7 years

To all whom it may concern:

Be it known that I, Robert Z. Snyder, a citizen of the United States and a resident of Philadelphia, county of Philadelphia, State of Pennsylvania, have invented a new, original, and ornamental Design for a Radio Cabinet, of which the following is a specification, reference being had to the accompanying drawing, forming a part thereof, wherein:

The figure is a perspective view showing the de-

sign of the radio cabinet and particularly the front construction thereof, it being pointed out that the rear surface of the cabinet is similar in appearance to the front surface of the cabinet cover which latter is shown swung into partially opened position.

I claim:

The ornamental design for a radio cabinet, as shown and described.

ROBERT Z. SNYDER.
